UNITED STATES PATENT OFFICE.

BYRON B. GOLDSMITH, OF NEW YORK, N. Y.

DESIGN FOR A PAPER-CLIP.

47,558.

Specification for Design.

Patented July 13, 1915.

Application filed April 29, 1914. Serial No. 835,318. Term of patent 14 years.

To all whom it may concern:

Be it known that I, BYRON B. GOLDSMITH, a citizen of the United States, residing in the city, county, and State of New York, have invented a new, original, and ornamental Design for Paper-Clips, of which the following is a specification, reference being had to the accompanying drawings, forming part thereof.

The figure is a plan view of the clip showing its novel design.

The clip has the form of a wire bent at its

middle portion approximately into a circle and then bent in short portions extending away from the center of the circle and finally having its extremities bent first away from each other in a substantially straight line as shown and then made to converge substantially in a V-shape, so that the extremities come close together.

I claim—

The ornamental design for a paper clip as shown and described.

BYRON B. GOLDSMITH.
